TENSION DEVICE FOR SPINNING AND TWISTING FRAMES

Fred K. Hendrickson, Worcester, Mass., assignor to Whitin Machine Works, Whitinsville, Mass., a corporation of Massachusetts

Application April 8, 1940, Serial No. 328,488

19 Claims. (Cl. 57—105)

This invention relates to spinning and twisting frames and more particularly to the mechanism for driving the spindles in such machines.

It is customary to arrange rows of spindles along the opposite sides of spinning and twisting frames and to drive these spindles by tapes or bands from centrally located pulleys or drums. Commonly two spindles on each side of a frame are driven by a single tape.

Special devices are required for tensioning the driving tapes, and these devices must be operative with the cylinder revolving in either direction, as the direction of rotation will be reversed according to the desired twist in the yarn.

It is the general object of my invention to provide improved tensioning devices for spinning and twisting frames, so designed that they can be used to advantage on narrow frames where previously known tensioning devices could not be used.

A further object is to provide tensioning devices which are simple in construction and compact in arrangement and which are convenient and reliable when in use.

My invention further relates to arrangements and combinations of parts which will be herein-after described and more particularly pointed out in the appended claims.

A preferred form of the invention is shown in the drawings, in which

Fig. 1 is a transverse sectional elevation of parts of a twisting frame embodying my improvements;

Fig. 2 is a diagrammatic plan view showing the usual arrangement of spindles and tapes;

Fig. 3 is an enlarged side elevation of my improved tensioning device; and

Fig. 4 is a plan view, looking in the direction of the arrow 4 in Fig. 3.

Referring to the drawings, I have shown parts of a twister frame comprising a frame member 10 mounted on adjustable stands 11 and supporting spindle rails 12 and longitudinally extending frame bars 14 and 15. A rectangular rod 17 is also supported on the frame members 10 and extends longitudinally of the frame for a purpose to be described.

A series of driving pulleys 20 are mounted on a driving shaft 21 supported in bearings 22 on the frame members 10. The shaft 21 is positively rotated in either direction by any suitable driving means, not shown and forming no part of my present invention.

Spindles 25 are mounted on the spindle rails 12 and are provided with driving pulleys or whirirs

26 engaged by tapes 30. The usual arrangement of spindles is as shown in Fig. 2, with a single tape 30 passing around the driving pulley 20 and engaging the whirirs 26 of two spindles on each side of the machine.

Spools S are mounted on the spindles 25, and separators 32 may be supported on the bars 15 to prevent interference between the yarns of adjacent spools.

The parts thus far described, with the exception of the rectangular bar 17, are or may be of usual commercial construction. I will now describe the improved devices which I provide for automatically tensioning the tapes and taking up slack, regardless of the direction in which the pulleys 20 are rotated.

For this purpose, I provide guide pulleys 40 and 41 (Fig. 3) mounted on hangers 42 and 43 which in turn are pivoted at 44 and 45 on brackets 46 and 47 which are recessed to fit snugly over the rectangular supporting bar 17 and which may be secured thereon by clamping screws 48.

Weighted levers 50 and 51 are pivoted at 52 and 53 on the brackets 46 and 47 respectively. The extended ends 54 and 55 of the levers 50 and 51 are engaged by the overhanging end portions 56 and 57 of the hangers 42 and 43. Fixed stops 60 and 61 on the brackets 46 and 47 are positioned for engagement on their upper sides by lugs 62 and 63 on the lever extensions 54 and 55, and on their lower sides by lugs 64 and 65 on the hangers 42 and 43.

The brackets 46 and 47 are forked as indicated in Fig. 4, so that the hangers 42 and 43 and the levers 50 and 51 are very firmly supported. It will also be noted by reference to Figs. 3 and 4 that the parts are so mounted and arranged that a minimum transverse space is required, although the pulleys 40 and 41 rotate in the same plane and guide the belt 30 in said plane.

Assuming that the pulley 20 is rotating anti-clockwise or in the direction of the arrow a in Fig. 3, the portion of the tape 30 at the left of Fig. 3 will be under driving stress and will swing the guide pulley 40 and hanger 42 to the left to raise the weighted lever 50 until the lug 62 on said lever 50 engages the fixed stop 60, which stop determines the fixed running position of the pulley 40 when the driving pulley 20 is rotating anti-clockwise.

In the meantime, the pulley 41, which is not under driving stress, will be swung to the left by its weighted lever 51 until it firmly engages the tape 30 and automatically takes up any slack in said tape. Such movement to the left, however,

is not of such extent as to cause the lug 65 to engage the stop 61 under usual operating conditions.

If, however, the tape 30 should break, both pulleys 40 and 41 would swing toward the center of the machine until the lugs 64 and 65 engage the lower sides of the stops 60 and 61. The pulleys are thus retained approximately in running position, so that replacement of the tape 30 may be conveniently effected.

When the direction of rotation of the pulley 20 is reversed, the pulley 41 moves to the right to a fixed position, and the pulley 40 takes up the slack.

I have thus provided very convenient and compact tensioning devices by which a tape, as 30, may be guided and kept from running loose or slack, regardless of the direction of rotation of the driving pulley.

While I have shown only a single set of spindles, driving pulleys and tensioning devices in the drawings, it is common to provide these parts in two banks, with a second set of spindles, driving pulleys and tensioning devices mounted on upward extensions of the frame members 10. The construction, so far as the belt guiding and tensioning devices are concerned, is, however, identical with the construction shown in Figs. 3 and 4 and already described.

Having thus described my invention and the advantages thereof, I do not wish to be limited to the details herein disclosed, otherwise than as set forth in the claims, but what I claim is:

1. Tension devices for spindle-driving tape in a spinning or twisting machine comprising a supporting structure mounted in said machine, a pair of swinging hangers pivoted on said structure, one at each side of the longitudinal center line of said machine, a guide pulley pivoted on each hanger, weighted levers for said hangers pivoted on said structure, one at each side of said center line and between the associated hanger and said center line, and each hanger and its associated lever having coacting extensions which render said parts effective to move the associated pulley to take up slack when engaging a non-driving run of said tape.

2. Tension devices for spindle driving tape in a spinning or twisting machine comprising a supporting bar extending longitudinally of said machine, supporting structure mounted on said bar, a pair of swinging hangers pivoted on said structure, one at each side of said bar, a guide pulley pivoted on each hanger, weighted levers for said hangers pivoted on said structure, one at each side of said bar and between the associated hanger and said bar, each hanger and its associated lever having coacting extensions which render said parts effective to move the associated pulley to take up slack when engaging a non-driving run of said tape, and said structure having fixed stops to limit outward movement of each pulley when engaging a driving run of said tape.

3. Tension devices for spindle-driving tape in a spinning or twisting machine comprising a supporting bar extending longitudinally of said machine, supporting structure mounted on said bar, a pair of swinging hangers pivoted on said structure, one at each side of said bar, a guide pulley pivoted on each hanger, weighted levers for said hangers pivoted on said structure, one at each side of said bar and between the associated hanger and said bar, each hanger and its asso-

ciated lever having coacting extensions which render said parts effective to move the associated pulley to take up slack when engaging a non-driving run of said tape, and said structure having fixed stops engaged by said lever extensions and thereby limiting outward movement of either pulley when engaged by a driving run of said tape.

4. Tension devices for spindle-driving tape in a spinning or twisting machine comprising a supporting bar extending longitudinally of said machine, supporting structure mounted on said bar, a pair of swinging hangers pivoted on said structure, one at each side of said bar, a guide pulley pivoted on each hanger, weighted levers for said hangers pivoted on said structure, one at each side of said bar and between the associated hanger and said bar, each hanger and its associated lever having coacting extensions which render said parts effective to move the associated pulley to take up slack when engaging a non-driving run of said tape, and said structure having fixed stops engaged by said hangers and limiting movement of said pulleys toward each other if suddenly released by breaking of the tape.

5. Tension devices for spindle-driving tape in a spinning or twisting machine comprising a supporting bar extending longitudinally of said machine, supporting members mounted on said bar, a pair of swinging hangers pivoted on said members, one at each side of said bar, a guide pulley pivoted on each hanger, and levers pivoted on said members between said hangers and said rod, said levers crossing above said rod and each having a weighted end portion beyond said rod, and said levers and hangers having extensions coacting between their pivots, whereby each weighted lever acts to swing the guide pulley on the associated hanger yieldingly toward the weighted end of said lever.

6. Tension devices for spindle-driving tape in a spinning or twisting machine comprising a supporting bar extending longitudinally of said machine, supporting members mounted on said bar, a pair of swinging hangers pivoted on said members, one at each side of said bar, a guide pulley pivoted on each hanger, and levers pivoted on said members between said hangers and said rod, said levers crossing above said rod and each having a weighted end portion beyond said rod, and said levers and hangers having extensions coacting between their pivots, whereby each weighted lever acts to swing the guide pulley on the associated hanger yieldingly toward the weighted end of said lever, said members, hangers and levers being identical, and said pulleys being mounted to rotate in the same plane.

7. A tension device for a spindle-driving tape in a spinning or twisting frame comprising a supporting bar extending longitudinally of the machine, brackets mounted in adjacent pairs on said bar and extending therefrom in opposite directions, swinging hangers pivoted on said brackets, a guide pulley pivoted on each hanger, and a separate weighted lever for each pulley pivoted on each bracket, each hanger and associated lever being mounted on the same bracket and having abutting and coacting extensions which render said parts effective to move the associated pulley only to take up slack when engaging a non-driving run of said tape.

8. A tension device for a spindle-driving tape in a spinning or twisting frame comprising a supporting bar extending longitudinally of the ma-

chine, brackets mounted in adjacent pairs on said bar and extending therefrom in opposite directions, swinging hangers pivoted on said brackets, a guide pulley pivoted on each hanger, and a separate weighted lever for each pulley pivoted on each bracket and extending above and across said supporting bar, each hanger and associated lever being mounted on the same bracket and having abutting and coacting extensions which render said parts effective to move the associated pulley only to take up slack when engaging a non-driving run of said tape.

9. A tension device for a spindle-driving tape in a spinning or twisting frame comprising a supporting bar extending longitudinally of the machine, brackets mounted in adjacent pairs on said bar and extending therefrom in opposite directions, swinging hangers pivoted on said brackets, a guide pulley pivoted on each hanger, and a weighted lever pivoted on each bracket, each hanger and associated lever being mounted on the same bracket and having coacting extensions which render said parts effective to move each pulley to take up slack when engaging a non-

driving run of said tape, and each lever crossing said supporting bar and having a weighted end at the side of said bar opposite from the pivot of said lever.

5 10. A tension device for a spindle driving tape in a spinning or twisting frame comprising a supporting bar extending longitudinally of the machine, brackets mounted in adjacent pairs on said bar and extending therefrom in opposite directions, swinging hangers pivoted on said brackets, a guide pulley pivoted on each hanger, and a weighted lever pivoted on each bracket, each hanger and associated lever being mounted on the same bracket and having coacting extensions 15 engaging between their pivots and which render said parts effective to move each pulley to take up slack when engaging a non-driving run of said tape, each lever crossing said supporting bar and having a weighted end at the side of said bar opposite from the pivot of said lever, and each bracket having a stop effective to limit swinging movement of its associated hanger and pulley in 20 both directions.

FRED K. HENDRICKSON.
